UNITED STATES PATENT OFFICE.

LOUIS F. PFISTER, OF BROOKLYN, NEW YORK, ASSIGNOR TO THE CUTLER-HAMMER MFG. CO., OF MILWAUKEE, WISCONSIN, A CORPORATION OF WISCONSIN.

ROLL-CHANGER FOR WEB-PRINTING PRESSES.

1,250,217.

Specification of Letters Patent. Patented Dec. 18, 1917.

Application filed July 31, 1913. Serial No. 782,330.

To all whom it may concern:

Be it known that I, LOUIS F. PFISTER, a citizen of the United States, residing at Flatbush, Brooklyn, in the county of Kings and State of New York, have invented new and useful Improvements in Roll-Changers for Web-Printing Presses, of which the following is a full, clear, concise, and exact description, reference being had to the accompanying drawing, forming a part of this specification.

This invention relates to roll changers for web printing presses.

The modern high-speed web printing press requires a web roll of large size. Space limitations in printing establishments, however, require that the space allotted to each press be reduced to a minimum.

An object of the present invention is to provide a roll changer for web printing presses by means of which the rolls may be changed in a minimum space.

Another object of the invention is to provide improved means by which the new roll may be easily and rapidly substituted for a spent roll without interfering with the continuous operation of the press.

A preferred form which this invention may assume is illustrated in the accompanying drawings, in which:

Figure 1 is a side elevation.

Fig. 2 is a section on a plane parallel to the elevation shown in Fig. 1, illustrating the positions assumed by the various parts during the operation of changing the rolls.

Fig. 3 is a plan view with the driving shaft omitted.

Fig. 4 is a vertical section on the line A—B, Fig. 3.

Fig. 5 is an enlarged longitudinal section through a web roll and its shaft.

Fig. 6 is a section on the line C—D, Fig. 5.

A pair of parallel roll supporting arms 1 and 2 are each supported on trunnions 3 which have their bearings in any convenient support which may be a portion of the press frame. Each end of the said arms is slotted as at 4 and 5 to provide slideways for split bearing boxes 7, 8, 9 and 10 in which web roll shafts 11 and 12 are rotatably mounted. Springs 13 uphold the bearing boxes in the outer ends of the slideways. The bearing boxes are prevented from being forced out of the slideways by removable locking

pins 14 inserted through eye bolts 15 in the 55 end of the arms and engaging slotted projections 16 on the outer portion of each bearing box. Seats for each end of the springs are provided by stubs 17 and 18 projecting respectively from the inner ends of the 60 slideways and the inner sections of the bearing boxes.

Each web roll shaft is provided with a pair of grooved rollers 19 removably mounted on the shaft and, except as herein-after explained, freely rotatable with relation thereto. One roller of each pair is provided with a pair of pivoted spring-pressed pawls 20 adapted to coöperate with a ratchet 21 keyed to the shaft. As illustrated in Fig. 5, the ratchet may be carried by the extended end of a chuck 22 which co-operates with a chuck 23 to position the web roll on the shaft. If desired, each of the rollers may be provided with the spring-pressed pawls, in which case, of course, ratchets would be provided on each of the chucks.

The grooved rollers coöperate with a pair of curved tracks 24 arranged between the 80 roll supporting arms and preferably secured to any convenient portion of the press frame. The tracks describe an arc of comparatively large radius, each track extending between the corresponding ends of the 85 roll shafts.

Suitable tension devices of any preferred type may be employed to control the unwinding of the web. As illustrated, each web roll shaft may be provided with a 90 brake drum 25. Adjustable brake bands 26 and 27 pivoted at 28 and 29 to sliding blocks 30 coöperate with each drum. The free ends of each pair of brake bands are adjustably drawn together by screws 31. Suitable 95 guideways 32 are provided for the sliding blocks so that the brake bands may slide with the roll shafts as hereinabove described.

It is customary in web roll presses to provide means for adjusting the rolls longitudinally so that they may accurately aline with the printing mechanism. In order to provide for this adjustment the rollers 19 have been made slightly wider than the tracks and the guideways 32 have been arranged to 105 permit the necessary slight movement of the blocks 30. Adjusting screws 33 are threaded through the blocks 30 and into any con-

2
5
venient portion of the press frame to determine this adjustment. By changing the adjustment of the screws the roll shafts may be moved longitudinally a slight distance to properly align the rolls.

10
15
The arms 1 and 2 carrying the web roll shafts may be rotated about the trunnions 3 by any preferred mechanism. As illustrated, a worm-wheel 34 carried by one trunnion is driven by a worm 35 on a driven shaft 36. Motion is communicated to the opposite trunnion through miter gears 37 and connecting shafts 38 so that the arms rotate in unison.

20
25
15
In Fig. 1 web roll 39 is supplying the paper which is drawn from the roll through a pair of nipping rollers 40 over an automatic tension roller 41 into the press. This web roll being nearly spent, a new roll 42 is represented as having been placed in position on the opposite ends of the roll supporting arms. This is accomplished by removing the locking pins 14, the split bearing boxes and removable grooved rollers, permitting a new roll to be readily placed on the web roll shaft.

30
35
The arms are then rotated about their trunnions in a clockwise direction by means of the gearing described. As the arms rotate the filled roll is moved inwardly toward the trunnions by means of its grooved rollers 19 which ride on the tracks 24.

40
45
50
55
The slideways formed by the slots 4 in the arms and the guides 32 for the brake band block permit free movement of the roll shaft against the tension of the spring 13. At the same time rotation is imparted to the roll 42 by means of the ratchet connection between the rollers 19 and the core of the roll. As the roll is moved farther toward the left (Fig. 2) it comes in contact with the web being drawn from the discharging roll 39. At this instant sufficient speed of rotation is imparted to roll 42 to cause its peripheral speed to substantially equal the speed of the web as it is drawn into the press. By means of an adhesive previously applied to the free end of the web on the roll 42, the fresh web is automatically pasted to the web from the roll 39 and is drawn into the press, the ratchet connection now permitting the web to be drawn off freely. The web from the roll 39 is then broken by a flystick or other means. The spent roll 39 may now be readily removed and another roll substituted in preparation for the next change.

60
65
In the embodiment illustrated the full roll is shown as drawn up out of the way to economize vertical space, although it is apparent that by repositioning the tracks, space in any other direction may be economized.

The illustration here given represents merely the preferred embodiment of the in-

vention as it is apparent that many modifications may be made which fall equally within the scope of the invention.

What I claim as new and desire to secure by Letters Patent is:—

70
1. The combination with a printing press in which the web roll is rotated by the web being unwound therefrom, of a roll changer comprising a movable support adapted to carry a plurality of web rolls, means for moving said support to move a full roll into the position of a spent roll, said support being designed to bring the full roll into contact with the web from the spent roll, and means for imparting a rotary motion to said 80 full roll before it makes contact with the web from the spent roll.

2. A roll changer for printing presses comprising a movable support carrying a plurality of web rolls, means for moving 85 said support to move a full roll into the position of a spent roll, said support being designed to bring the full roll into contact with the web from the spent roll, and means for rotating said full roll as it is moved to 90 replace the spent roll, said last named means acting only during the movement of the support.

3. A roll changer for printing presses comprising a movable support carrying a 95 plurality of web rolls, means for moving said support to move a full roll into the position of a spent roll, said support being designed to bring the full roll into contact with the web from the spent roll, and stationary means adapted to impart a rotary motion to the full roll as it is moved to replace the spent roll.

4. A roll changer for printing presses comprising a movable support carrying a 105 plurality of web rolls, means for moving said support to move a full roll into the position of a spent roll, said support being designed to bring the full roll into contact with the web from the spent roll, and means 110 coöoperating with the web roll spindle for imparting a rotary motion to the full roll as it is moved to replace the spent roll.

5. A roll changer for printing presses comprising a movable support carrying a 115 plurality of web rolls, means for moving said support to move a full roll into the position of a spent roll, said support being designed to bring the full roll into contact with the web from the spent roll, and means 120 independent of the regular web roll rotating means for rotating the full roll as it is moved to replace the spent roll.

6. A roll changer for printing presses comprising a movable support carrying a 125 plurality of web rolls, means for moving said support to move a full roll into the position of a spent roll, said support being designed to bring the full roll into contact with the web from the spent roll, and a guide 130

coöperating with the roll spindle of the full roll to rotate said roll as it is moved to replace the spent roll.

7. A roll changer for printing presses comprising a movable support, a plurality of web rolls mounted thereon, means for moving said support to move a full roll to the position of a spent roll, said support being designed to bring the full roll into contact with the web from the spent roll, and means coöperating with the roll spindle of the full roll to rotate said full roll in the direction of travel of the web of the spent roll as said full roll is moved to replace said spent roll.

8. A roll changer for printing presses comprising a movable support, a plurality of web rolls mounted thereon, means for moving said support to move a full roll to the position of a spent roll, and means coöperating with the roll spindle of the full roll to rotate said full roll in the direction of travel of the web of the spent roll as said full roll is moved to replace said spent roll, and means for preventing said full roll from rotating in the opposite direction.

9. A roll changer for printing presses comprising a movable support carrying a plurality of web rolls, means for moving said support to move a full roll to the position of a spent roll, means independent of the regular web roll rotating means for rotating the full roll in the direction of movement of the web of the spent roll as the full roll is moved to replace said spent roll, and means for preventing said full roll from rotating in the opposite direction.

10. A roll changer for printing presses comprising a movable support pivoted near its center and carrying a web roll adjacent each end thereof, means for rotating the support to move a full roll to the position of a spent roll, and means for automatically moving one of said rolls toward the center of said support as said support is rotated whereby the positions of the rolls may be changed in a minimum space.

11. A roll changer for printing presses comprising a movable support pivoted near its center and carrying a web roll adjacent each end thereof, means for rotating the support to move a full roll to the position of a spent roll, means for automatically moving one of said rolls toward the center of said support as said support is rotated whereby the positions of the rolls may be changed in a minimum space, and means coöperating with the spindle of the full roll for rotating said full roll in the direction of travel of the web of the spent roll as the full roll is moved to replace said spent roll.

12. A roll changer for printing presses comprising a movable support adapted to carry a plurality of web rolls, means for moving said support to move a full roll into

the position of a spent roll, and means for moving one of said rolls toward the other as their positions are changed so that the change may be made in a minimum space.

13. A roll changer for printing presses comprising a movable support adapted to carry a plurality of web rolls, means for moving said support to move a full roll into the position of a spent roll, and means for rotating said full roll as it is moved to replace the spent roll, said means being adapted to move the full roll toward the spent roll as their positions are changed.

14. A roll changer for printing presses comprising a movable support pivoted near its center, web roll spindles movably mounted on said support on each side of said pivot, said spindles being yieldingly held near the ends of said support, means for moving said support about its pivot to interchange the positions of said spindles, and means for moving one of said spindles toward the pivot during the movement of the support so that the interchange may be made in a minimum space.

15. A roll changer for printing presses comprising a movable support pivoted near its center, web roll spindles movably mounted on said support on each side of said pivot, means for moving said support about its pivot to interchange the positions of said spindles, and means for moving one of said spindles toward the pivot and for rotating said spindle during the movement of the support to replace the spent roll with a full roll.

16. A roll changer for printing presses comprising a movable support pivoted near its center, web roll spindles movably mounted on said support on each side of said pivot, said spindles being yieldingly held near the ends of said support, means for moving said support about its pivot to interchange the positions of said spindles and an arcuate guide adapted to move one of said spindles toward the pivot of the support and to rotate said spindle during the movement of the support to interchange the positions of the spindles.

17. A roll changer for printing presses comprising a movable support pivoted near its center, web roll spindles rotatably mounted in slidable bearings yieldingly held near the ends of said support, means for moving said support about its pivot to interchange the positions of said spindles and an arcuate guide adapted to move one of said spindles toward the pivot of said support and to rotate said spindle during the movement of the support to interchange the positions of said spindles.

18. The combination with a printing press in which the web roll is rotated by the web being unwound therefrom, of a roll changer comprising a movable support adapted to

carry a plurality of web rolls, means for moving said support to move a full roll into the position of a spent roll, said support being designed to bring the full roll into contact with the web from the spent roll, driving means for imparting a rotary motion to said full roll before it makes contact with the web from the spent roll and means whereby the full roll may be rotated independently of said driving means.

19. A roll changer for printing presses comprising a movable support, means for moving said support, a plurality of web rolls slidably mounted on the support and means for moving one of the rolls relative to the support as said support is moved to cause the one roll to approach the other.

20. The combination with a printing press in which the web roll is rotated by the web being unwound therefrom, of a roll changer comprising a movable support adapted to carry a plurality of web rolls, means for moving said support to move a full roll into the position of a spent roll, said support being designed to bring the full roll into contact with the web from the spent roll, driving means for imparting a rotary motion to said full roll before it makes contact with the web from the spent roll and a pawl and ratchet associated with the driving means whereby the full roll may be rotated independently of the driving means.

21. A roll changer for printing presses comprising a movable support, means for moving said support, a plurality of web rolls slidably mounted on the support, means for causing one of said rolls to approach the other as the support is moved and means for automatically returning the roll to its original position relative to the support as the support reaches the end of its movement.

22. A roll changer for printing presses comprising a movable support, a plurality of web rolls mounted thereon, means for moving the support to shift a full roll to the position of a spent roll, means for rotating the full roll in the direction of travel of the web as said roll is moved to replace the spent roll and means for insuring that the roll rotates in one direction only.

23. A roll changer for printing presses having a movable support adapted to carry a plurality of web rolls, means for moving said support, means for causing one of said rolls to be moved relative to the support as said support is moved and means for automatically returning said roll to original position relative to the support.

24. A roll changer for printing presses comprising a pivoted support, a plurality of web rolls slidably mounted on said support, means for moving said support, an arcuate guide adapted to move one of said

rolls relative to said support and to impart a rotary motion to the roll and means to insure that the rotation is in one direction only.

25. In a rapid roll changer for web printing presses, a rotatable roll carrier, a web roll mounted adjacent one end thereof, and means whereby as said roll carrier is rotated said web roll is moved inwardly from the end thereof.

26. In a rapid roll changer for web printing presses, a rotatable roll carrier, a pair of web rolls mounted thereon, means for rotating said roll carrier to interchange the positions of said rolls, and automatic means for moving one of said rolls toward the pivot of said carrier as said carrier rotates.

27. In a rapid roll changer for web printing presses, a pair of rotatable slotted roll supporting arms, a pair of web rolls rotatable in bearings slidable in the slots in said arms, guide rails adjacent said arms, and means on said web rolls coöperating with said guide rails to cause said bearings to slide in said slots as said arms are rotated.

28. In a rapid roll changer for web printing presses, a pair of rotatable slotted roll supporting arms, a pair of web rolls rotatable in bearings slidable in the slots in said arms, guide rails adjacent said arms, and means on said web rolls coöperating with said guide rails to cause said bearings to slide in said slots as said arms are rotated.

29. In a rapid roll changer for web printing presses, a pair of rotatable roll supporting arms, a pair of web rolls rotatably mounted in bearings slidable on said arms, curved tracks adjacent said arms, and means on said web rolls coöperating with said tracks whereby as said arms are rotated said web rolls are caused to slide relatively to said arms.

30. In a rapid roll changer for web printing presses, a pair of rotatable roll supporting arms, a pair of web rolls rotatably mounted in bearings slidable on said arms, means tending to hold said bearings adjacent the ends of said arms, curved tracks adjacent said arms, and means on said web rolls coöperating with said tracks whereby as said arms are rotated said web rolls are caused to slide against the action of said holding means and relatively to said arms.

31. In a rapid roll changer for web printing presses, a pair of rotatable roll supporting arms provided with longitudinal slots extending inwardly from the ends thereof, a pair of web roll shafts rotatably and slidably mounted in said slots, springs forcing said shafts to the outer ends of said slots, a pair of curved tracks each extending approximately between the ends of the arms, rollers on said roll shafts coöperating with said tracks, web rolls mounted on said roll shafts, and a pawl and ratchet connection

between said rollers and said web rolls whereby as said arms are rotated said rollers may cause one of said web rolls to slide inwardly in said slots and simultaneously to rotate.

- 5 32. In a rapid roll changer for web printing presses, a pair of independently rotatable roll supporting arms provided with longitudinal slots extending inwardly from 10 the ends thereof, means for causing said arms to rotate in unison, a pair of web roll shafts rotatably and slidably mounted in said slots, springs for forcing said shafts to the outer ends of said slots, a pair of 15 curved tracks each extending approximately between the opposite ends of the arms, rollers on said roll shafts coöperating with said tracks, web rolls mounted on said roll shafts, and connections between said rollers and

said web rolls whereby as said arms are rotated said rollers cause one of said web rolls to slide inwardly in said slots and simultaneously to rotate.

33. A roll changer for printing presses comprising a rotary support carrying a plurality of web rolls, means for rotating said support to move a full roll into the position of a spent roll, and means for rotating said full roll as it is moved to replace the spent roll, said last named means acting only during the movement of the support.

In witness whereof, I have hereunto subscribed my name in the presence of two witnesses.

LOUIS F. PFISTER.
